US00D825837S

(12) **United States Design Patent** (10) Patent No.: **US D825,837 S**
(45) Date of Patent: **** Aug. 14, 2018**

(54) **HAND-HELD AEROSOL GENERATOR**

- (71) Applicant: **Philip Morris Products S.A.**, Neuchatel (CH)
- (72) Inventors: **Aaron Abroff**, Acton, MA (US); **Gregor Mittersinker**, Warwick, RI (US); **Laurent Manca**, Grandvaux (CH)
- (73) Assignee: **Philip Morris Products S.A.**, Neuchatel (CH)
- (**) Term: **15 Years**
- (21) Appl. No.: **29/626,023**
- (22) Filed: **Nov. 14, 2017**

Related U.S. Application Data

- (62) Division of application No. 29/553,180, filed on Jan. 29, 2016, now Pat. No. Des. 811,651, and a division of application No. 29/479,202, filed on Jan. 13, 2014, now Pat. No. Des. 759,296, which is a division of application No. 29/425,439, filed on Jun. 22, 2012, now Pat. No. Des. 699,391.

(30) **Foreign Application Priority Data**

(57)

CLAIM

The ornamental design for a hand-held aerosol generator, as shown and described.

DESCRIPTION

FIG. 1 is a perspective view of a hand-held aerosol generator showing our new design as viewed from the left side of the page;

FIG. 2 is a side elevational view of one side thereof;

FIG. 3 is a top plan view thereof;

FIG. 4 is a side elevational view of the opposite side thereof;

FIG. 5 is a bottom plan view thereof;

FIG. 6 is a front plan view thereof; and,

FIG. 7 is a rear plan view thereof.

1 Claim, 4 Drawing Sheets
